UNITED STATES PATENT OFFICE.

NATALIE A. TEEPLE, (NOW BY MARRIAGE NATALIE A. STOLP,) OF PHILADELPHIA, PENNSYLVANIA.

MEANS OF PROTECTION FOR FEMININE WEAR.

1,109,264.

Specification of Letters Patent.

Patented Sept. 1, 1914.

Application filed October 4, 1913. Serial No. 793,299.

To all whom it may concern:

Be it known that I, NATALIE A. TEEPLE, a citizen of the United States, and a resident of Philadelphia, in the county of Philadelphia and State of Pennsylvania, have invented certain new and useful Means of Protection for Feminine Wear, of which the following is a specification.

It is well known that rude and flirtatious youths and men, "mashers", frequently avail themselves of the crowded condition of cars and other means of transportation to annoy and insult ladies next whom they may happen to be seated by pressing a knee or thigh against the adjacent knee or thigh of their feminine neighbor, who, as often happens is too timid or modest to create a disturbance by calling attention to the fact.

It is the object of my invention to guard against undue familiarity of the character designated by the provision of means whereby the offender is automatically warned, punished, and deterred from persistent offense; and to this end my invention consists primarily of an elastic resilient spring arranged in conjunction with a spur or prick and adapted to be attached to an under-skirt in such manner that when subjected to extraneous pressure the sharp point will protrude; and secondarily, of such minor details of construction as are herein described and claimed specifically.

In the accompanying drawings, Figure 1, is a side elevation and Fig. 2, a front view of a simple form of my device; Fig. 3, a side view of a modification and Fig. 4, a front view thereof; Fig. 5, is a side view of another modification and Fig. 6, a front view thereof; Fig. 7, a side view of the device in its simplest form and Fig. 8, a front view thereof.

The essential features of the invention are a base *b*, adapted to be attached to an undergarment, an elastic resilient guard spring *s*, mounted on said base, and a pricker *p*, arranged to protrude upon the compression of said guard spring.

In the accompanying drawings I have illustrated several forms in which my protector may be made without intending to limit myself strictly thereto, since it is obvious that various modifications may be resorted to without departing from the spirit and intent of my invention.

Thus in Figs. 1 and 2 the pricker *p*, is

fixed to the base *b*, and the elastic resilient spring *s*, is formed with a slot or recess *s'*, through which the point of the pricker will protrude when the spring is compressed,—the bow or curvature of the spring providing the necessary extent of motion to effect this result.

In Figs. 3 and 4 the pricker *p*, is mounted upon a comparatively straight tongue *p'*, attached to the elastic resilient spring *s*, the bow or curvature of which latter, when straightened out by pressure renders it longer than the tongue *p'*, so that the end of the latter will then be released from the shoulder *s²*, allowing the point of the pricker *p*, to rest against the curved end *s³*, of the spring, and if the spring *s*, is compressed sufficiently, carrying said end *s³*, beyond the pricker *p*, and allowing the latter to protrude. Thus for instance, accidental or slight pressure applied to this form of the protector will release the pricker from the detaining shoulder *s²*, to be still shielded by the return bend *s³* but upon the second application of pressure, or where the pressure exerted is intentional and maintained, the point of the pricker *p*, will be released and rendered effective.

Perhaps the simplest possible practical embodiment of my automatic protector is to form the pricker *p*, directly on the end of the elastic resilient spring *s*, itself, in which case the point may be either protected normally by a pivoted shield *a*, as in Figs. 5 and 6 to be turned by finger pressure when the point is to be rendered operative, or the bow or increased curvature of the spring *s*, may be relied upon, as in Figs. 7 and 8, to ward and fend off contact with the point unless unusual pressure is exerted on the bow of the spring. In any case the base *b*, forms a means of attachment to an under-skirt or garment, and is also essential in that it affords the requisite bearing and resistance to render the protector operative and effective in use.

The device is simple and inexpensive and adapted to be concealed and worn without obtrusion or inconvenience; and if properly positioned on an undergarment, will afford ample individual protection against misconduct of the character designated.

What I claim as my invention and desire to secure by Letters Patent is,

1. A protector of the character designated

comprising a base adapted for attachment to an undergarment, an elastic-resilient spring mounted thereon, and a pricker arranged to protrude upon the compression of the spring for the purpose described.

2. In a protector of the character designated, the combination of the base *b*, elastic resilient spring *s*, formed with the retaining shoulder *s²*, and bent end *s³*, and the tongue *p'*, and pricker *p*, arranged and operating in the manner and for the purpose set forth.
3. A protector of the character designated

comprising a base adapted for attachment to an undergarment, and a pricker and an elastic-resilient spring mounted thereon in such manner that the spring protects the point of the pricker until said spring is compressed thereby causing the point of the pricker to protrude.

NATALIE A. TEEPLE.
